The ornamental design for a handle, as shown and described.

(30) **Foreign Application Priority Data**

DESCRIPTION

May 2, 2012 (EM) 002036111-0013

FIG. 1 is a left side elevational view of a handle of the present invention.

(51) **LOC (9) Cl.** **23-01**

FIG. 2 is a right side elevational view of the handle of FIG. 1.

(52) **U.S. Cl.**

FIG. 3 is a front elevational view of the handle of FIG. 1.

USPC **D23/252**

FIG. 4 is a rear elevational view of the handle of FIG. 1.

(58) **Field of Classification Search**

FIG. 5 is a top plan view of the handle of FIG. 1.

USPC D23/238-243, 250, 252; 4/675-678;

FIG. 6 is a bottom plan view of the handle of FIG. 1; and,

137/801

FIG. 7 is a perspective view of the handle of FIG. 1.

See application file for complete search history.

The dashed lines illustrate environment that does not form a part of the present invention, and no claim is made to the material illustrated with dashed lines.
